(74) Attorney, Agent, or Firm — ALLEN, DYER ET AL.

(57) **CLAIM**

The ornamental design for a pattern for a golf cart floor mat, as shown and described.

DESCRIPTION

FIG. 1 is a top view of a design for a pattern for a golf cart floor mat;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top perspective view of thereof; and,

FIG. 7 is an enlarged view from the top perspective view for a pattern for a golf cart floor mat.

The broken lines shown illustrate portions of the pattern for a golf cart floor mat that form no part of the claimed design.
